UNITED STATES PATENT OFFICE.

RICHARD P. WILLIAMS, OF NEW YORK, N. Y., ASSIGNOR TO THE LORAIN STEEL COMPANY, A CORPORATION OF PENNSYLVANIA.

TONQUE-SWITCH.

No. 834,432.

Specification of Letters Patent.

Patented Oct. 30, 1906.

Application filed June 28, 1904. Serial No. 214,440.

To all whom it may concern:

Be it known that I, RICHARD P. WILLIAMS, of the borough of Brooklyn, city of New York, in the county of Kings and State of New York, have invented a new and useful Improvement in Tongue-Switches, of which the following is a full, clear, and exact description, reference being had to the accompanying drawings, which form a part of this specification.

My invention has relation to certain new and useful improvements in tongue-switches, and is designed to provide a switch in which the use ^{c'} of the deep-bearing heel-pin usually employed is obviated; also, to provide means whereby the tongue is securely held down to its seat on the bed of the structure and is thereby prevented from kicking or accidental throwing; also, to provide a construction in which the tongue can be readily and quickly removed when necessary to repair and renew it.

With these objects in view my invention consists in the novel construction and combination of parts, all substantially as hereinafter described, and pointed out in the appended claims, reference being had to the accompanying drawing in which—

Figure 1 is a plan view of a tongue-switch embodying my invention; Fig. 2, a partial longitudinal section taken on the line 2 2 of Fig. 1; Fig. 3, a plan view of the switch-tongue removed; Fig. 4, a transverse section on the line 4 4 of Fig. 1, and Fig. 5 a detail view of the locking-plate.

The letter A designates the body portion of the structure, which is formed with a seat ^a for the movable tongue B. Said tongue is provided at its heel with a depending cylindrical projection ^b, which terminates at its lower end in a circular enlargement or flange ^{b'}. The portions ^b and ^{b'} may be formed integrally with the tongue B, or they may be secured thereto. To receive the convex heel end of the tongue and the portion ^b, the body structure is formed with the convex bearing-seat ^c, and to receive the flange portion ^{b'} it is formed with the undercut bearing ^{c'}. To permit the tongue to be seated, the bed ^a is recessed, as shown at ^{a'}.

D is a locking and bearing member or plate which is inserted in the recess ^{a'} after the tongue is seated with its concave edge ^d in bearing engagement with the portions ^b ^{b'}.

It is then secured in place by means of the keys or wedges E, driven behind it. F designates a hard bearing-plate, which is preferably seated underneath the flange portion ^b of the tongue, but which may be omitted.

In the manner described I form a secure and efficient bearing for the tongue which obviates the use of the long heel-pin usually employed. The plate E, in connection with the undercut bearing ^{c'}, also forms secure means for holding the tongue down to its seat to prevent its "kicking" and accidental throwing. The tongue can be readily removed at any time by loosening the keys or wedges F and removing the plate D, which can be done without disturbing the balance of the structure in its position in the track. To facilitate the removal of the plate D, the recess ^{d'} may be provided. The wear in the bearing may also be taken up at any time by driving the keys or wedges or by removing them and re-driving them against shims or liners.

I do not wish to limit myself to the precise construction which I have herein shown and described, as various changes may be made in the details thereof without departing from the spirit and scope of my invention.

Having thus described my invention, what I claim as new, and desire to secure by Letters Patent, is

1. In a tongue-switch, the combination with a switch-tongue having a depending bearing member at its heel portion, of a locking member arranged to engage and disengage the bearing member by horizontal movement.

2. In a tongue-switch, the combination with a switch-tongue having a depending flanged bearing member, of a locking-plate engaging said bearing member, and means for removably securing the locking-plate.

3. In a tongue-switch, the combination with the body portion of the structure having an undercut bearing for the end of a switch-tongue, of a tongue having a flanged member engaging said bearing, and a locking-plate engaging said flanged member.

4. In a tongue-switch, the combination with the body portion having the undercut bearing at its heel portion, of the tongue having the depending flanged bearing member engaging said bearing, the removable locking-plate, and the removable keys or wedges which secure said locking-plate.

5. In a tongue-switch, the combination with the body portion of the structure having a bed or seat for a tongue, said bed being recessed and undercut at its heel portion and a hard bearing-plate seated in said recess, of a tongue having a depending flanged bearing member engaging the undercut of the body portion and bearing on said plate and a removable locking member seated in said recess and engaging said bearing member.
6. In a tongue-switch, a switch-tongue having at its heel a depending projection, terminating at its lower end in a circular horizontal flange of larger diameter than the body portion of the projection.
7. In a tongue-switch, the combination with a switch-tongue having a depending pin at its heel end, of a holding and bearing member for the front portion of the pin, arranged to move horizontally toward and away from the same, together with means for securing said member.
8. In a tongue-switch, the combination with a switch-tongue having a depending pin at its heel end, of a holding and bearing member for the front portion of the pin, arranged to move horizontally toward and away from the same, and a wedge for securing and adjusting the said bearing member.
9. In a tongue-switch, the combination with a body portion having an undercut portion at the heel, of a tongue having a large bearing-pin which extends under the said undercut portion, and a removable bearing and locking member in front of said pin and movable horizontally toward and away from the same, together with means for holding and adjusting the said member in engagement with the said pin.
10. In a tongue-switch, the combination with a switch-tongue having a bearing-pin at its heel end, provided with a rear bearing against the body of the structure, a horizontally-movable bearing-piece in front of said pin, means for securing the same in engagement with the pin, and a hard-metal bearing-piece for the lower end of the said pin.
11. In a tongue-switch, the combination with an undercut body portion, of a tongue having a large bearing-pin extending under the said undercut body portion, a hard-metal bearing-plate for the lower end of said pin, and a removable locking and bearing member arranged to engage and disengage the front portion of said pin by horizontal movement, together with wedge devices for holding and adjusting said locking and bearing member.

In testimony whereof I have affixed my signature in presence of two witnesses.

RICHARD P. WILLIAMS.
